UNITED STATES PATENT OFFICE

LOUIS V. ARONSON, OF NEWARK, NEW JERSEY

TOY GUN

Application filed April 26, 1928. Serial No. 272,976.

The invention relates to toys and has as an object the provision of a toy gun providing the combination of muzzle illuminating means with explosion simulating means.

5 It is a further object of the invention to provide a gun having in combination means to simulate the flash of the muzzle of the gun with means to produce a sound simulating the explosion of the gun wherein the two are 10 simultaneous so as to give a realistic simulation of the discharge of a gun.

It is a further object of the invention to provide a toy as described in the form of a machine gun.

15 It is a further object of the invention to provide a toy as described in which successive simulations of the discharge may be brought about with considerable rapidity whereby to simulate the action of a machine gun.

20 It is a further object of the invention to provide combined muzzle flashes with explosive sounds closely synchronized with an entire absence of fire hazard and which cannot harm the user.

25 Further objects of the invention will appear from the following description when read in connection with the accompanying drawings showing an illustrative embodiment of the invention and wherein:

30 Figure 1 is a side elevation;

Fig. 2 is a plan view;

Fig. 3 is a vertical longitudinal section on line 3—3 of Fig. 2;

Fig. 4 is a vertical transverse section on line 4—4 of Fig. 1;

Fig. 5 is a detail side elevation from the left of Fig. 4 with the casing removed;

Fig. 6 is a vertical longitudinal section on line 6—6 of Fig. 2 showing a different position of the parts from that shown in Fig. 3;

Fig. 7 is a detail vertical transverse section on line 7—7 of Fig. 1 and

Fig. 8 is a vertical transverse section on line 8—8 of Fig. 1.

45 As shown the device is embodied in a toy simulating a machine gun having a base 10 preferably formed of hollow sheet metal with a bottom 11 desirably lined upon its lower surface with felt as at 12. To support the 50 mechanism of the toy there is shown an in-

verted U-shaped bracket 13 secured to the base 10 by means of bolts 14 and having the upwardly projecting portions engaging the side members 15, 16 of the frame of the device, which members are shown as secured to the member 13 by screws 17, 18.

The side members 15, 16 are spaced apart but connected together by a portion 19 integral with the side members and utilized to support a cylinder 20 to be described.

To present an outer configuration resembling a machine gun, there is shown a casing 20 carrying rigidly therewith the barrel 21 which casing is slipped over the frame of the device housing the mechanism therein and formed with a slot 22 through the upper portion of which the operating shaft 23 for the mechanism projects, the slot being provided for convenience in placing the casing over the mechanism and for passage of the shaft 70 in assembly.

A shield for the toy is shown at 24 formed with an opening which enables the shield to be slipped over the barrel 21, the margin of the opening being formed with an integral 75 ear 25 secured to the barrel as by means of a screw 26 and said shield carrying a U-shaped member 27 rigidly secured thereto, the arms 28 of the U-shaped member being shown as secured to the casing 20 by means 80 of screws 29.

To simulate a flash from the muzzle of the gun there is shown an abradant surfaced wheel 30 journaled in a member 31 secured to the interior of the muzzle of the gun, desirably formed in U-shape, one of the ears of the U carrying arms 32, 33, and the U-shaped member being inserted in an opening 34 in the muzzle of the gun with the arms 32, 33 secured to the outer surface of the barrel by 90 screw bolts 35, 36.

The remaining ear of the U-shaped member 31 is shown as carrying a cylinder 37 adapted to house a pyrophoric element spring 95 pressed against the abradant surface of wheel 30 by means of an arm 38 having a pressure finger 39, said arm 38 being pivoted at 40 upon the exterior of the gun barrel and forming a bell crank the arm 41 of which is connected to a spring 42 which is anchored to 100

a lug 43 struck inwardly from the material of the barrel.

The arm 38 is shown as forwardly arched so that its top may simulate the front sight 5 for the gun, a rear sight being provided in the form of a perforation 103 in the shield 24.

The wheel 30 is shown as journaled for free revolution upon its stub shaft 44 and is adapted to be revolved by means of a pinion 10 45 meshing with a rack 46 carried by an arm 47 brought into operation by a mechanism to be described.

The sparking means at the muzzle of the gun may be constructed as shown in my former Patent No. 1,598,034, dated August 31, 15 1926.

To permit the show of the sparks produced from the pyrophoric material 48 when the 20 sparking mechanism is operated there are shown a plurality of perforations in the barrel of the gun adjacent its muzzle.

To cause a fireless explosion in synchronism with the illumination of the muzzle of the gun, there is provided means for suddenly 25 rupturing a strip of paper by compressed air. To this end the cylinder 20 is shown as provided with a reduced opening 50 in its upper wall and to compress air in the cylinder there is shown a piston 52 sliding therein bearing a 30 piston rod 53 pivoted at 54 to one arm of a bell crank 55 rigidly mounted upon a shaft 56 journaled in the side members 15, 16 of the frame. The other arm 57 of the bell crank carries a pin 58 coacting with a cam 59 rigidly 35 carried by shaft 23, which shaft is also journaled in the side members 15, 16 and which shaft may be operated by means of a crank 60 exterior of the casing 20. The cam is shown as formed to gradually force the arm 40 57 of the bell crank forwardly with depression of the piston 52 and sudden release thereof when the pin 58 escapes from the point 61 of the cam.

To return the bell crank 57 to normal position, there are shown relatively heavy coiled 45 springs 62, 63, one anchored to each arm of the bell crank, the spring 62 being anchored at 64 upon a bar 65 serving as a spacing member for the sides 15, 16 of the frame and the spring 50 63 being anchored upon the end of an arm 66 projecting rearwardly from the member 15, as shown in Figure 3.

To operate the sparking mechanism in exact synchronism with the rupturing of the 55 paper, there is shown a link 67 pivotally attached to the arm 57 of the bell crank by means of a stub shaft 68 shown as an extension of the pin 58 upon which the cam 59 operates, a roller 69 being desirably placed upon said 60 pin 58 to reduce friction.

The stub shaft 68 is shown as projecting through an arcuate slot 70 in the side member 16 of the frame to bring the link 67 exteriorly of the frame and the link is shown as 65 projecting through a slot 71 in the casing 20

and through a slot 72 in the shield 24 and as pivotally connected to a downwardly projecting arm 73 carried by the end of the bar 47 and projecting through a slot 74 in the end of the barrel 21.

To carry a supply of paper to be ruptured, there is shown a roll of paper at 75 rotatably mounted in arms 76, 77 upon a removable pin 78, which pin may be removed for renewal of the roll when exhausted. The paper is led from the roll through a cutaway portion 79 of the casing 20 over the opening 50 in the cylinder and under a feed roll 80 journaled in arms 81 projecting from the other side of the casing 20, which feed roll has a roughened surface against which the paper is pressed by means of a resilient member 82 secured at its upper end adjacent the lower margin of the cutaway portion 79 and has its lower end curved about the feed roll as shown at 83.

To operate the feed roll 80, there is shown a mutilated gear 84 carried upon the projecting end of shaft 23 having teeth 85 upon a portion only of its periphery, which teeth coact with a pinion 86 rigidly carried by the end of a longitudinal shaft 87 journaled in a bearing 88 secured to the inner surface of the side member 15, the forward end of shaft 87 carrying a pinion 89 meshing with a gear 90 carried by the supporting shaft of roller 80. Because of the mutilation of gear 84, the roller 80 will be operated only during downward movement of piston 52 in the cylinder and the paper will remain stationary at the time of its rupture.

To press the paper tightly against the reduced opening 50 of the cylinder at the moment of its rupture there is shown a member 91 pivoted upon a shaft 92 carried by the side members 15, 16 having a horizontal portion 93 provided with an opening 94 through which the rupture of the paper takes place. To press the member 93 against the paper the member 91 is shown as rigidly connected with an arm 95 having a pin 96 on its end coacting with a cam 97 rigidly mounted upon the shaft 23 and said arm 95 being distanced to normally raise the member 91 by means of a coiled spring 98 anchored to the arm and to the side member 15 as at 100.

To close the cut-away portion 79 of the frame, there is shown a portion 101 pivoted at 102 to the side members of the casing 20. The operation of the device will be clear from the above description.

Minor changes may be made in the physical embodiment of the invention within the scope of the appended claims without departing from the spirit thereof.

I claim:

1. A toy gun comprising, in combination, a barrel, a mount therefor, flash producing means located adjacent the muzzle of the barrel, pneumatic explosion producing means, an operating shaft and means where-

by continuous rotation of said shaft repeatedly operates the flash producing means and the pneumatic explosion producing means in synchronism.

5. 2. A toy gun comprising, in combination, a barrel having a breach, a mount therefor, flash producing means located in the barrel, pneumatic explosion-simulating means located at said breach, an operating shaft rotatable about a horizontal axis, and means whereby continuous rotation of said shaft repeatedly operates the flash producing means and the pneumatic explosion simulating means in synchronism.

10. 3. A toy gun comprising, in combination, a barrel and a mount therefor, the barrel being mounted at its breach on the mount, pyrophoric sparking means located adjacent the muzzle of the barrel, a cylinder located adjacent the breach of the barrel, said cylinder having an opening in one end, means feeding a strip of paper over said opening, a piston operating in said cylinder, a rotary shaft, and means whereby continuous rotation of the shaft repeatedly operates the sparking means and piston in synchronism.

15. 4. A toy gun comprising, in combination, a barrel and a mount therefor, the barrel being mounted at its breach on the mount, pyrophoric sparking means located adjacent the muzzle of the barrel, a cylinder located adjacent the breach of the barrel, said cylinder having an opening in one end, means feeding a strip of paper over said opening, 20 a piston operating in said cylinder, a rotary shaft, and means whereby continuous rotation of the shaft repeatedly operates the sparking means and piston in synchronism, and means whereby such rotation of said 25 shaft operates to feed the paper intermittently between the sparking operations produced by the sparking means.

40. 5. A toy gun comprising, in combination, a barrel, flash producing means located for producing a flash from the muzzle of the barrel, pneumatic explosion simulating means located adjacent the breach of the barrel, and means for actuating both of said means in synchronism, said actuating means comprising a rotary shaft, a cam carried by said shaft, a lever operated by the cam, a link connected to said lever and extending through the barrel to operate said flash producing means and means connected to said lever to 45 operate said explosion simulating means.

5. 6. A toy gun comprising, in combination, a barrel having an opening on its lower side adjacent the muzzle thereof, a frame member inserted in the barrel through said opening and having an ear extending along the underneath side of the barrel and secured thereto, a pyrophoric member carried by said frame member, means for abrading said pyrophoric member, and a spring pressed lever pivoted 50 on the top of said barrel for pressing said

pyrophoric member into engagement with said abrading means.

7. A toy gun comprising, in combination, a barrel, a cylinder having an opening at one end, a reel of paper on one side of said opening, the paper being adapted to pass over said opening, a reel on the other side of said opening on which paper is wound up, a piston in said cylinder, a spring for moving the piston in one direction, and means for retracting the piston against said spring and actuating said wind-up reel simultaneously.

10. 8. A toy gun comprising, in combination, a barrel, a vertically arranged cylinder adjacent the breach of said barrel, said cylinder having an opening in its top, a reel of paper on one side of the cylinder, the paper being adapted to pass over said opening to the other side of the cylinder, a reel on said other side of the cylinder on which said paper is wound up, a piston in said cylinder, and means for operating said piston and wind-up reel in synchronism.

15. 9. A toy gun comprising, in combination, a barrel, a vertically arranged cylinder adjacent the breach of said barrel, said cylinder having an opening in its top, a reel of paper on one side of the cylinder, the paper being adapted to pass over said opening to the other side of the cylinder, a reel on said other side of the cylinder on which said paper is wound up, a piston in said cylinder, and means for operating said piston and wind-up reel in synchronism, said last mentioned means comprising a spring operating the piston in one direction, a shaft rotatable about a horizontal axis, a cam on said shaft, means whereby said cam operates said piston in the opposite direction in opposition to said spring and suddenly releases the same, and means operated by the shaft for operating the wind-up reel when the cam operates the piston but permits the wind-up reel to remain stationary when the spring operates the piston.

20. 10. A toy gun comprising in combination, a barrel, a vertically arranged cylinder adjacent the breach of said barrel, said cylinder having an opening in its top, a reel of paper on one side of the cylinder, the paper being adapted to pass over said opening to the other side of the cylinder, a reel on said other side of the cylinder on which said paper is wound up, a piston in said cylinder, a pivotally mounted pressure member over said cylinder having an opening cooperating with the opening in the top of the cylinder, the paper passing horizontally between the top of the cylinder and the pressure member, and means for operating said piston, take-up reel and pressure member in synchronism.

25. 11. A toy gun comprising, in combination, a cylinder having an opening in one end, means feeding a strip of paper over said opening, a pivotally mounted pressure member adapted to press the paper toward said

- opening, a piston in said cylinder, a spring acting to operate the piston to rupture the paper, a cam shaft and means operated by the cam shaft for operating the piston, paper feed and pressure member in synchronism.
12. A toy gun comprising, in combination, a mount, a barrel mounted thereon, an upright shield located at the rear of the barrel and through which the barrel extends, flash producing means located at the muzzle of the barrel, a cylinder located behind said shield, a piston in said cylinder, said cylinder having an opening in one end, means for feeding a strip of paper over said opening, a pressure member also located behind said shield and arranged to press the paper toward said opening and mechanism also behind said shield for operating said piston, paper feeding means, pressure member and flash producing means in synchronism.
13. A toy gun comprising, in combination, a barrel, an upright shield adjacent the breach of the barrel and through which the barrel extends, pneumatic paper rupturing explosion simulating means located behind said shield, mechanism for operating the same behind said shield, a casing substantially enclosing said explosion simulating means and operating mechanism about the top and sides thereof, said casing having an opening opposite said explosion simulating means, and a door located behind said shield for closing said opening.
14. A toy gun comprising, in combination, a mount, a barrel mounted thereon, an upright shield located at the rear of the barrel and through which the barrel extends, flash producing means located at the muzzle of the barrel, a cylinder located behind said shield, a piston in said cylinder, said cylinder having an opening in one end, means for feeding a strip of paper over said opening, a pressure member also located behind said shield and arranged to press the paper toward said opening and mechanism also behind said shield for operating said piston, paper feeding means, pressure member and flash producing means in synchronism, a casing substantially enclosing the cylinder, pressure member and operating mechanism at the top and sides thereof, said casing having an opening at the top thereof through which the paper may be adjusted, and a hinged door for closing said opening.
15. A toy gun or the like comprising in combination a barrel and a mount therefor, actuating mechanism housed in said mount, pyrophoric sparking mechanism mounted in said barrel, explosion simulating means housed in said mount, a cam forming a portion of said mechanism, means operable by said cam to simultaneously actuate said explosion simulating means and said sparking mechanism and means to manually actuate said cam.
16. A toy gun or the like comprising in combination, a barrel, a mount therefor, actuating mechanism housed in said mount, a crank exterior of said mount for actuating of said mechanism, pyrophoric sparking means housed in said barrel adjacent the muzzle thereof, a cylinder housed in said mount having a reduced opening, means to direct paper across said opening, a piston reciprocating in said cylinder, a cam operable by said crank, means operated by said cam for depression and sudden release of said piston, a spring to return said piston to normal position in said cylinder whereby to rupture said paper, a link operable by said cam to actuate said pyrophoric sparking means.
17. A toy gun or the like comprising in combination, a mount, a barrel carried by said mount, actuating mechanism housed in said mount comprising a cam mounted on a shaft projecting to the exterior of the mount, a crank for actuation of said shaft, pyrophoric sparking mechanism mounted in said barrel adjacent the muzzle thereof, a cylinder housed in said mount and having a reduced opening, means actuated by said mechanism to feed paper across the opening in said cylinder, a piston in said cylinder spring pressed toward said paper, means operable by said cam to depress said piston against the action of said spring and to suddenly release the same whereby to rupture said paper with explosive action, means operable by said cam to actuate said sparking mechanism, means to hold said paper firmly against said opening at the moment of rupture and a cam mounted upon said shaft acting to depress said paper holding means at the instant of rupture of the paper.
18. A toy gun or the like comprising in combination, a mount, a barrel carried by said mount, actuating mechanism housed in said mount comprising a cam mounted on a shaft projecting to the exterior of the mount, a crank for actuation of said shaft, pyrophoric sparking mechanism mounted in said barrel adjacent the muzzle thereof, a cylinder housed in said mount and having a reduced opening, means actuated by said mechanism to feed paper across the opening in said cylinder, a piston in said cylinder spring pressed toward said paper, means operable by said cam to depress said piston against the action of said spring and to suddenly release the same whereby to rupture said paper with explosive action, means operable by said cam to actuate said sparking mechanism, means to hold said paper firmly against said opening at the moment of rupture, a cam mounted upon said shaft acting to depress said paper holding means at the instant of rupture of the paper, and means operable by said shaft to feed paper across said opening intermittently between instants of rupture thereof.
19. A toy gun or the like comprising in

combination, a mount housed in actuating mechanism, a barrel supported on said mount, pyrophoric sparking means housed in said barrel adjacent the muzzle thereof, said mechanism comprising a cam rigidly mounted upon a shaft projecting to the exterior of the mount, a crank mounted upon said shaft for manual actuation of said cam, a cylinder housed in said mount having a reduced opening, a piston reciprocating in said cylinder, a bell crank forming a portion of said mechanism, one arm of said bell crank pivotally secured to a piston rod carried by said piston, a spring connected to said arm for urging the piston towards the opening of the cylinder, the remaining arm of the bell crank having operative relation to said cam, said cam so formed that its revolution depresses the piston in the cylinder against the action of the spring and suddenly releases the same, a link connected to the cam end of said bell crank operatively connected to said sparking means, a supply roll of paper pivotally supported upon the exterior of the mount to simulate a cartridge belt, said paper extending across the reduced opening in said cylinder, means journaled upon the exterior of the opposite side of the mount to feed said paper across the opening, means whereby revolution of said shaft causes intermittent feeding of said paper between moments of release of said piston, means to press the paper about said opening at the moment of its rupture whereby actuation of the crank causes simultaneous actuation of said sparking means and the rupture of the paper by release of said piston.
